George Wells,
Inventor.

United States Patent Office.

GEORGE WELLS, OF BETHEL, CONNECTICUT.

Letters Patent No. 71,828, dated December 3, 1867.

IMPROVED DOOR-HOLDER.

The Schedule referred to in these Letters Patent and making part of the same.

TO ALL WHOM IT MAY CONCERN:

Be it known that I, GEORGE WELLS, of the township of Bethel, in the county of Fairfield, and State of Connecticut, have invented certain novel and useful Improvements in Door-Stops or Holders; and I hereby declare the following to be a full, clear, and exact description of the same, reference being had to the accompanying drawings, which are lettered to correspond with and form a part of the specification.

In order that the public may fully understand the nature of my invention, and those skilled in mechanics be enabled to construct and use the same, I will describe it as follows, to wit:

Figure 1 is a perspective drawing of my improved door-stop, having the hood or cap removed to show the segmental cogged cocking foot-lever A, which operates the eccentric or cam B that causes the looped bolt or fall C to move up or down when operated by the foot or otherwise. D is an India-rubber or other flexible pad to prevent the bolt C from wearing out the carpet. This pad constitutes the foot of the fall or bolt C, and when used upon the bare floor it prevents bruising the same, and adheres more tenaciously to the wood, consequently holds the door at any fixed angle or required position.

Figure 2 is a perspective vertical view of the side of the cap and fall C, with India-rubber pad D and foot-lever A, the whole being secured to the bottom of the door by means of screws passing through the bed-plate S, fig. 1.

Figure 3 is a perspective side and front view of the exterior of the cap secured to the plate S by screw-pins; also showing the segmental cogged foot-lever A which operates the stop or holder C and D.

The nature of my invention consists in the looped or other bolt C, provided with a flexible pad, D, at the lower end thereof, and operated by means of an eccentric or cam and segmental cogged gear A, for the purpose of holding a door at any required opening or angle. The cap and bed-plate S may be cast in one piece, or, if separate, as shown in the drawings, may be secured together by any suitable device in lieu of screw-pins.

Therefore, what I claim as new and useful, and what I wish to secure by Letters Patent of the United States, is—

1. The bolt or fall C and pad D, operated in the manner and for the purpose set forth.
2. I claim the foot-lever A in combination with the eccentric or cam B, or an equivalent thereof, to operate the bolt or holder C, for the purpose substantially as described and shown in the drawings.

I testify whereof, I hereunto subscribe my name in the presence of two witnesses.

GEORGE WELLS.
